UNITED STATES PATENT OFFICE.

ARTHUR OLINE, OF MINDEN, NEBRASKA.

STAPLE EXTRACTOR OR PULLER.

1,269,845.

Specification of Letters Patent. Patented June 18, 1918.

Application filed December 15, 1916. Serial No. 137,149.

To all whom it may concern:

Be it known that I, ARTHUR OLINE, a citizen of the United States, residing at Minden, in the county of Kearney, State of Nebraska, have invented a new and useful Staple Extractor or Puller; and I do hereby declare the following to be a full, clear, and exact description of the invention, such as will enable others skilled in the art to which it appertains to make and use the same.

This invention relates to a new and useful staple extractor or puller and an object of the invention is to provide a simple, efficient and practical tool of this kind, having means whereby a staple may be easily and quickly extracted.

A further object of the invention is to provide a device of this kind in which improved features of construction are involved.

One of the features of construction is to provide a tool consisting of a body, one end terminating in a handle, the other end shaped to form a lateral loop, the free extremity of which constitutes a prong so tapered to a point as to enable the point to be driven under a staple by the blows from a hammer or the like, so that when the handle is moved downwardly the staple may be extracted.

By inserting or driving the free extremity of the loop partially under the staple, the staple may be partly drawn, when moving the handle downwardly, then by further inserting the tapered part or prong of the loop and moving the handle in the opposite direction, the staple may be further extracted.

Further, that by the provision of a tool of this kind, the lateral loop thereof may be disposed in engagement under and through the staple (after the same has been extracted a certain distance) in order that a further pull may be imparted, whereby the staple may be finally extracted.

In practical fields, the details of construction may necessitate alterations falling within the scope of what is claimed.

The invention comprises further features and combination of parts, as hereinafter set forth, shown in the drawings and claimed.

50 In the drawings:—

Figure 1 is a view in perspective of the improved staple extractor, showing the application of the same, that is, illustrating how an initial pull is imparted to the staple.

55 Fig. 2 is a view in side elevation, illustrating

how the final pull may be imparted to completely extract the staple.

Referring more especially to the drawings, 1 designates an elongated tool shank consisting of a cylindrical part 2 and a part 3 rectangular in cross section. The end of the part 3 merges into a curved portion 4, which extends at an obtuse angle to the shank. This portion 4 merges into a substantially semi-circular curved portion 5, which terminates in a tapering sharp pointed hook or prong 6, which extends nearly in parallelism with that portion of the tool between the curved portions 4 and 5 of the lateral loop 7. This prong or hook curves slightly in a direction from the end of the rectangular portion 3, so that said hook may obtain a grip under the arch head 8 of the staple 9 when extracting the same. It is to be noted that the hook or prong 6 extends in a plane at such an angle to the tool shank that when the hook or prong is in engagement with the staple to be extracted, a post or the like, as shown in Fig. 1, the shank may extend laterally and slightly upwardly, whereby upon a downward pull of the handle, the staple may be partially extracted. The prong or hook may then be further inserted, so that by another pull downwardly, or a pull upwardly, may further extract the staple. Then by inverting the tool to permit the loop 7 to be inserted under the arch of the staple and between its sides, the staple may be finally withdrawn from the post or the like, as shown in Fig. 2. It is to be noted that the prong or hook 6 is so bulged that the loop and the extremity of the prong will engage the surface from which the staple projects.

The invention having been set forth, what is claimed as new and useful, is:—

In a staple extractor, a tool shank, substantially one half its length being rectangular in cross section, one end of said rectangular portion terminating in a loop, the side of the loop adjacent the shank being substantially at an obtuse angle to the tool shank, the other side of the loop tapering into a curved prong curved outwardly and in a direction from the side which is at an obtuse angle to the tool shank and adapted to engage under the crotch of the staple to give it an initial pull, the outer opposite faces of the sides of the loop being substantially in parallelism and constituting bear-

ings, one to engage the crotch of a staple, the other engaging the face of a member into which the staple is driven, whereby a final pull may be exerted on the staple by means of said loop, the terminal of the prong constitutes means on which the extractor may be fulcrumed when exerting such a final pull.

In testimony whereof I have signed my name to this specification in the presence of 10 two subscribing witnesses.

ARTHUR OLIN.
